UNITED STATES PATENT OFFICE.

OTTO A. HENSEL, OF PITTSBURG, PENNSYLVANIA.

DESIGN FOR AN EGG-BEATER.

SPECIFICATION forming part of Design No. 24,545, dated August 13, 1895.

Application filed May 28, 1895. Serial No. 551,020. Term of patent 3½ years.

To all whom it may concern:

Be it known that I, OTTO A. HENSEL, a citizen of the United States, residing at Pittsburg, in the county of Allegheny and State of Pennsylvania, have invented a new and original Design for an Egg Beater or Agitator, of which the following is a specification, reference being had to the accompanying drawing, showing a part thereof, and in which I have shown

5 o a perspective view of my design for an egg beater or agitator, which view is all that is necessary to illustrate my design.

The leading feature of my design consists in the form of the propeller-shaped blades at

5 the bottom of a cylindrical shank.

In the drawing, 1 is the shank, cylindrical in form and having arranged at the base two propeller-shaped blades 2 and 3, the one 2 bent upwardly, having the point at one side

curved or bent to the front and the other to 20 the rear. The lower blade 1 is analogous in form, only arranged in position with the points of the same projecting in opposite directions to those of the blades 2 above. These blades are each perforated with circular openings 4 arranged in parallel rows. The lower portion or end of the shank 1 is conical in form.

What I claim is—

The design for an egg beater or agitator 30 substantially as shown and described.

In testimony whereof I affix my signature in presence of two witnesses.

OTTO A. HENSEL.

Witnesses:

RICHARD S. HARRISON,
JOHN C. THOMPSON.
